ELECTRIC HAND LANTERN

John W. Baer, Woodside, and Otto Karl Reinhardt, Jamaica, N. Y., assignors to Bond Electric Corporation, Jersey City, N. J., a corporation of Delaware

Application November 16, 1934, Serial No. 753,268

3 Claims. (Cl. 240—10.63)

This invention relates to electric hand lanterns of the kind in which replaceable batteries constitute the source of electricity.

One object of the present invention is a hand lantern of the character described which is provided with a readily insertable and replaceable unit containing the sources of light and electrical energy. Accordingly, a transparent hollow body member is provided with a removable cap and a combined lamp socket support and battery container, as a separable unit, is adapted to be removably inserted within the transparent body and preferably held in place by the cap.

Another object of the invention is a circuit closer adapted to cooperate with the handle of the lantern for the purpose of automatically closing the circuit when the lantern is suspended by the handle, but which is normally in circuit open position.

Still another object of the invention is the provision of a cap or top for the lantern with which the circuit closer is associated.

The invention also seeks an electric hand lantern of the character described which is practical from the standpoint of ease and cheapness of manufacture and durability and simplicity in use.

These and other objects of the invention and the means for their attainment will be more apparent from the following detailed description, taken in connection with the accompanying drawing, illustrating one embodiment by which the invention may be realized and in which:

Figure 1 is a view in vertical section showing the hand lantern of this invention, the circuit closing bail being in closed circuit position;

Figure 2 is a vertical sectional view, taken in the plane indicated by the line 2—2 of Figure 1 and looking in the direction of the arrows, the circuit closing bail being in open circuit position; 40 and

Figure 3 is a transverse sectional view, taken in the plane indicated by the line 3—3 of Figure 2, looking in the direction of the arrows.

In the illustrated embodiment, the electric hand lantern of this invention comprises generally a transparent body or globe 5, which is preferably integral with a base portion 6 formed as a base receiving member by the provision of threads 7 blown into the glass of which the body member 5 is conveniently made, the cylindrical base portion 6 having threaded thereon a base or bottom 8, say, of metal, adapted to stand upon a horizontal support and hold the lantern in an upright position.

The transparent body member 5 is preferably formed at its upper end with a tubular portion 10

whereof the interior surface is conveniently cylindrical and the outer surface, near the top thereof, is also formed with threads 11 for the reception of a top 12, also conveniently of metal. Above the threads the outer peripheral surface, as at 13, is cylindrical.

This cylindrical portion 13 receives a substantially U-shaped carrier member 15, which is conveniently shaped from a relatively narrow ribbon of sufficiently stiff conductive material, such as metal, so that the interior surfaces thereof are cylindrical to receive or hold a battery, shown in the illustrated embodiment as a single cell 16. The vertical sides 17 of the carrier frame are of a length slightly greater than the average height of a dry cell battery, the lower portions of the side members 17 being bent inwardly and at an angle, as at 18, to form, in effect, a shoulder, if desired, below which the battery cannot extend. The bottom of the frame 20 is conveniently flat and serves as a lamp socket support being formed on the axis of the carrier with an aperture 22 conveniently mutilated to form a thread, as will be understood, as a lamp socket for the reception of the threaded base 23 of the lamp 24. The elevation of the shoulder 18 above the support 20 is less than the length of the threaded portion of the lamp base 23 so that when a lamp is threaded into the aperture 22, the central or positive terminal 25 of the battery will rest upon the central terminal of the lamp base to form an electrical connection therewith. It will, of course, be understood that the battery 16 is wrapped or encircled with a non-conducting casing 26 such as the usual wrapper of fibrous material and hence the zinc cup is out of electrical contact with the carrier frame 17 although the bottom of the cup is exposed to serve as the negative terminal 27 of the cell. At its upper end the carrier frame is bent outwardly, as at 28, and downwardly as the hooks 29 to fit over the upper edge of the transparent body 5 at the cylindrical portion 13 thereof, as shown. Thus the hook portions 28, 29 are in electrical connection with one terminal of the lamp 24.

In the illustrated embodiment the cap 12 is shown as taking the form of the usual lantern cap or top resting on and in electrical connection with the hook shaped supporting portions 28, 29 of the lamp socket support 17, 18, 20, and having the upper cylindrical cup shaped portion 30 whereof the periphery is formed, in diametrically opposite portions thereof, with the apertures 31 through which the ends 32 of the bail 33 extend and whereby the bail is pivotally mounted on the

cap and movable between the position shown in Figure 2 in a plane transversely of the lantern to the vertical position shown in Figure 1.

It will be appreciated that the conductive carrier 17, 18, 20 is in electrical connection with the peripheral terminal of the lamp base and is also in electrical connection with the conductive cap 12, which in turn is in electrical connection with the bail 33, which passes through the holes 31 in the cap. The inturned ends 32 of the bail are utilized as circuit closers to complete the electrical circuit through the battery to the central terminal of the lamp by contacting with the negative terminal 27 of the battery. The inturned ends 32 of the bail are therefore turned downwardly, as at 36, and then again turned inwardly, as at 37, to lie in a plane well below the transverse plane of the openings 31 and at a distance sufficient to contact with the bottom 27 of the zinc cup 20 of the battery 16 when the bail is in a plane parallel to or including the axis of the structure 17, 18, 20. Obviously, therefore, when the bail lies in the transverse position illustrated in Figure 2 or at intermediate position, the ends 37 are 25 out of contact with the bottom of the negative terminal of the battery, whereas when the lantern is held in the hand or suspended so that the bail occupies the position illustrated in Figure 1, the ends 37 contact with the battery to complete the 30 circuit and illuminate the lamp. Desirably, the resiliency in the ends 32, 36, 37, is such that, irrespective of the exact position of the battery in the carrier frame 17, 18, 20, the ends 37 will 35 adjust themselves in making contact.

In the preferred embodiment, the battery is positioned in the support so as to be retained out of contact with the ends 37 when in circuit open position. To this end a battery positioning element takes the form of a ring or annulus 40, fixed 40 in the cap, as by the inwardly spun groove 41, so that no upward displacement of the battery is possible. This stop 40 is preferably of non-conductive material, such as fibre, so that no short circuit can occur between the cap 12 and the 45 negative terminal of the battery when the circuit closer is in open circuit position of Figure 2. The ends 36, 37 of the bail are, however, so shaped as to pass through the opening 41 in the annulus 40 to contact with the battery terminal 27 in circuit 50 closing position.

It will thus be seen that a very inexpensive electric hand lantern of few parts is provided in which the globe may be blown out of glass to receive a metal base and a metal cap. The hanger or battery carrying lamp socket is readily formed from a single strip of metal in a simple pressing operation and the cap and bail are similarly made of metal in a simple fashion. The device may be so constructed as to receive a single cell or a battery of cells.

Various modifications will occur to those skilled in the art in the composition, configuration and disposition of the component elements going to make up the invention as a whole, as well as in the 65 form of circuit closer incorporated in the invention and no limitation is intended by the phraseology of the foregoing specification or illustrations

in the accompanying drawing except as indicated in the appended claims.

What is claimed is:—

1. In an electric hand lantern, in combination, a transparent globe-like body member formed with threaded cylindrical upper and lower ends, at least said upper end being formed with a circular opening, a U-shaped conductive carrier frame formed with an aperture in its lowermost part whereof the edge is distorted to receive a lamp base and with outwardly turned upper ends to overlie the edge of the opening and be supported within the body and receive a battery, the central terminal of which is in electrical contact with the central terminal of the lamp, a removable base threaded on to the lower end of the body, a removable conductive cap for the globe-like body member formed with threads to engage the threads on the upper cylindrical portion of the body member and to contact with the ends of the carrier and a circuit closer adapted to selectively complete the electrical circuit comprising a bail whereof the ends are pivoted in the cap and so shaped as to contact with the other terminal of the battery when the bail is in one position of its movement. 15

2. In an electric hand lantern, in combination, a transparent globe-like body member formed with a threaded upper end, said upper end being formed with an opening, a U-shaped conductive carrier frame formed with a lamp socket support in its lowermost part and with outwardly turned ends to overlie the edge of the opening to be supported within the body member and receive a battery, a lamp socket carried with said support, the central terminal of said battery being in electrical contact with the central terminal of a lamp in said socket, a removable conductive cap for the globe-like body member formed with threads to engage the threads on the upper cylindrical portion of the body member and to contact with the ends of the carrier and a circuit closer adapted to selectively complete the electrical circuit comprising a bail whereof the ends are pivoted in the cap and so shaped as to contact with the other terminal of the battery when the bail is in one 30 position of its movement. 35

3. In an electric hand lantern, in combination, a transparent body member formed with an opening in its upper portion, a U-shaped conductive carrier frame having a lamp socket in its lowermost part and with outwardly extending portions to overlie the edge of the opening to be supported within the body member and receive a battery, the central terminal of which is in electrical connection with the central terminal of a lamp in said socket, a removable conductive cap for the opening in the body member and contacting with the outwardly extending portions of the carrier and a circuit closer adapted to selectively complete the electrical circuit comprising a bail whereof the ends are pivoted in the cap and so shaped as to contact with the other terminal of the battery when the bail is in one 40 position of its movement. 45

4. In an electric hand lantern, in combination, a transparent body member formed with an opening in its upper portion, a U-shaped conductive carrier frame having a lamp socket in its lowermost part and with outwardly extending portions to overlie the edge of the opening to be supported within the body member and receive a battery, the central terminal of which is in electrical connection with the central terminal of a lamp in said socket, a removable conductive cap for the opening in the body member and contacting with the outwardly extending portions of the carrier and a circuit closer adapted to selectively complete the electrical circuit comprising a bail whereof the ends are pivoted in the cap and so shaped as to contact with the other terminal of the battery when the bail is in one 50 position of its movement. 55
